(57) **CLAIM**

The ornamental design for a dress shirt with emoji pattern, as shown and described.

DESCRIPTION

FIG. 1 is a front view of a dress shirt with emoji pattern, showing my novel design;

FIG. 2 is a back view of the dress shirt with emoji pattern; FIG. 3 is a right side view of the dress shirt with emoji pattern;

FIG. 4 is a left side view of the dress shirt with emoji pattern; FIG. 5 is a top view of the dress shirt with emoji pattern; FIG. 6 is another top view of the dress shirt with emoji pattern;

FIG. 7 is a left-front perspective view of the dress shirt with emoji pattern;

FIG. 8 is right-front perspective view of the dress shirt with emoji pattern;

FIG. 9 is a back perspective view of the dress shirt with emoji pattern;

FIG. 10 is a right-top perspective view of the dress shirt with emoji pattern;

FIG. 11 is a left-top perspective view of the dress shirt with emoji pattern;

FIG. 12 is a bottom perspective view of the dress shirt with emoji pattern;

FIG. 13 is a duplicate of the view of FIG. 1, except for the broken line outlines that portray the bounds of the enlarged detail views shown in FIGS. 14-17;

FIG. 14 is an enlarged detail view taken from area 14 in FIG. 13;

FIG. 15 is an enlarged detail view taken from area 15 in FIG. 13;

FIG. 16 is an enlarged detail view taken from area 16 in FIG. 13;

FIG. 17 is an enlarged detail view taken from area 17 in FIG. 13;

FIG. 18 is a duplicate of the view of FIG. 9, except for the broken line outlines that portray the bounds of the enlarged detail view shown in FIG. 19;

FIG. 19 is an enlarged detail view taken from area 19 in FIG. 18;

FIG. 20 is a duplicate of the view of FIG. 10, except for the broken line outlines that portray the bounds of the enlarged detail view shown in FIG. 21;

FIG. 21 is an enlarged detail view taken from area 21 in FIG. 20;

FIG. 22 is a duplicate of the view of FIG. 11, except for the broken line outlines that portray the bounds of the enlarged detail view shown in FIG. 23;

(Continued)

FIG. 23 is an enlarged detail view taken from area 23 in FIG. 22;

FIG. 24 is a duplicate of the view of FIG. 12, except for the broken line outlines that portray the bounds of the enlarged detail views shown in FIGS. 25-26;

FIG. 25 is an enlarged detail view taken from area 25 in FIG. 24; and,

FIG. 26 is an enlarged detail view taken from area 26 in FIG. 24.

The enlarged detail views of FIGS. 14-17, 19, 21, 23, and 25-26 are shown separately from the claimed design as a whole for clarity of illustration.

The broken lines of the dress shirt and the broken lines within the emoji pattern depict portions of the article that form no part of the claimed design. All other broken lines indicate the boundaries of detail areas and form no part of the claimed design.

1 Claim, 26 Drawing Sheets
